CLAIM

The ornamental design for a wireless trailer light as shown and described.

DESCRIPTION

FIG. 1 is a top, front and left side perspective view of a wireless trailer light showing my new design;

FIG. 2 is a bottom, rear and right side perspective view thereof;

FIG. 3 is a top, rear and left side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of FIG. 6; and,

FIG. 11 is an enlarged view of FIG. 7.

The broken lines in the drawings illustrate portions of the wireless trailer light which form no part of the claimed design.

1 Claim, 11 Drawing Sheets
